(57) **CLAIM**

The ornamental design for a speaker, as shown and described.

DESCRIPTION

FIG. 1 is a front perspective view of a speaker showing our new design;

FIG. 2 is a front elevation view thereof;

FIG. 3 is a back elevation view thereof;

FIG. 4 is a left side elevational view thereof, the right side elevational view being a mirror image;

FIG. 5 is a top plan view thereof;

FIG. 6 is a bottom plan view thereof; and,

FIG. 7 is a section view taken along line 7—7 of FIG. 2. The broken lines showing the controls and connectivity ports in FIGS. 3 and 5, the feet in FIGS. 2-4 and 6 and 7, and the internal dimensions in FIG. 7 are for illustrative purpose only and form no part of the claimed design.
